CLAIM

The ornamental design for a scooter, as shown and described.

DESCRIPTION

FIG. 1 is a right side view of a scooter of the subject disclosure, the left side view being the same;

FIG. 2 is a top view thereof; and,

FIG. 3 is a front view thereof.

The broken lines shown are included for the purposes of illustrating portions of the scooter which form no part of the claimed design.

1 Claim, 3 Drawing Sheets

FIG. 1

FIG. 2

FIG. 3
